CLAIM

The ornamental design for a bracket for TV receiver, as shown and described.

DESCRIPTION

FIG. 1 is a front, right side, perspective view of a bracket for TV receiver showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-section view of 8-8 taken from FIG. 2;

FIG. 9 is a rear cross-section perspective view taken from the section cut shown in FIG. 2 in an environment of use; FIG. 10 is a cross-section view taken from the section cut shown in FIG. 2 in an environment of use; and,

FIG. 11 is an enlarged view of 11-11 taken from FIG. 10. The evenly-spaced broken lines in the drawings illustrate environment that forms no part of the claimed design. The dash-dot broken lines in FIG. 11 illustrate a boundary of the
